DESIGN.

—o—

J. WILLETS & W. S. LENOX.

TABLE WARE.

No. 16,534.

Patented Feb. 16, 1886.

UNITED STATES PATENT OFFICE.

JOSEPH WILLETS AND WALTER S. LENOX, OF TRENTON, NEW JERSEY.

DESIGN FOR TABLE-WARE.

SPECIFICATION forming part of Design No. 16,534, dated February 16, 1886.

Application filed December 19, 1885. Serial No. 186,233. Term of patent 3 $\frac{1}{2}$ years.

To all whom it may concern:

Be it known that we, JOSEPH WILLETS and WALTER S. LENOX, citizens of the United States, and residents of Trenton, in the county 5 of Mercer and State of New Jersey, have invented a new and original Design for Table-Ware, of which the following is a specification.

In the accompanying photographs, forming 10 a part of this specification, and in which like letters of reference indicate like parts in all the figures, Figure 1 is a face view of a plate showing our new design. Fig. 2 is a top view of a dish-cover showing our new design. Fig. 15 3 is a side view of a dish or tureen showing our new design.

The leading feature of our design consists 20 in a border, A, of leaves and branches or twigs, shown on the outer faces of the plates, covers, dishes, and tureens, along the edges of the same. At regular intervals some of the twigs or branches B of this border A project beyond the inner edge of the same, and on 25 said extended or projecting branches or twigs

B the leaves C are shown, which are larger 25 than the leaves on the remaining parts of the border. Of said larger leaves C, two on each branch or twig B are within the limits of the border, and one, which is on or near the end of the twig or branch B, is outside of the said 30 border. On the center of the plate the ornament D is shown, which consists of crossed twigs and creepers provided with leaves.

Having fully described our new design, what 35 we claim, and desire to secure by Letters Patent, is—

The design for table-ware herein shown and described, the same consisting of a border of twigs or branches, some of the branches projecting at intervals conspicuously beyond the 40 inner edge of the border, substantially as set forth.

JOSEPH WILLETS.
WALTER S. LENOX.
